Newton S. Taylor

UNITED STATES PATENT OFFICE.

NEWTON S. TAYLOR, OF CHICAGO, ILLINOIS.

TRACE-HOOK.

SPECIFICATION forming part of Letters Patent No. 229,019, dated June 22, 1880.

Application filed November 3, 1879.

To all whom it may concern:

Be it known that I, NEWTON S. TAYLOR, of Chicago, in the county of Cook and State of Illinois, have invented a new and useful Improvement in Trace-Hooks, which improvement is fully set forth in the following specification, reference being had to the accompanying drawings.

The object of my invention is to connect a common rope with the same for the purpose of using it as a harness-trace.

Figure 1 shows a section of rope-trace to which my improvement has been applied. Fig. 2 shows a device complete attached to a rope. The invention consists in the ferrule A, having a spiral groove (shown by line B) to fit the

strands of rope-trace C through its entire length, and a hook, E, on the end and side of ferrule A, in order that rope-trace C can pass by hook E in order to lengthen or shorten 20 rope-trace C by removing screws D.

I claim as my invention—

The improved trace-hook consisting of the spirally-grooved cylinder adapted to receive the strands of the rope, and provided with the 25 attaching-hook, all substantially as shown and described.

NEWTON S. TAYLOR.
